UNITED STATES PATENT OFFICE

140,700

DESIGN FOR A SEALED BEAM LAMP BULB

Saul I. Slater, Forest Hills, N. Y.

Application November 25, 1944, Serial No. 116,540

Term of patent 14 years

(Cl. D26—8)

To all whom it may concern:

Be it known that I, Saul I. Slater, a citizen of the United States, residing in Forest Hills, county of Queens and State of New York, have invented a new, original, and ornamental Design for a Sealed Beam Lamp Bulb, of which the following is a specification, reference being had to the accompanying drawing, forming part thereof.

Figure 1 is a front elevational view of the sealed beam lamp bulb showing my new design;

Figure 2 is a side elevational view thereof; and Figure 3 is a bottom plan view.

I claim:

The ornamental design for a sealed beam lamp bulb, as shown.

SAUL I. SLATER.
